UPROOTING IMPLEMENT

Carl P. Bohland and Carl E. Bublitz, Albert Lea,
Minn.

Application May 2, 1940, Serial No. 332,959

6 Claims. (Cl. 294—50.5)

Our invention relates to an implement designated generally as a weeder but more specifically is a device for uprooting and removing weeds such as dandelions and the like which have a main root usually extending directly down from the ground surface.

The main object is to provide a simple, inexpensive and highly efficient device of the class specified and in the use of which the operator need not at any time stoop over or reach down in any way for efficiently operating the device.

The invention consists, in general, of a novel arrangement construction and combination of parts, as hereinafter fully set forth, reference being had to the accompanying drawing, in which:—

Fig. 1 is a side elevation of our invention, showing the lower ends of the device inserted in the ground in operative position about to extract a weed.

Fig. 2 is a right side view of Fig. 1.

Fig. 3 is an enlarged left side view of approximately the lower half of Fig. 1 and Fig. 4 is a longitudinal section as on line 4—4 in Fig. 3.

Fig. 5 is an approximately full size sectional detail as on line 5—5 in Fig. 1.

Referring to the drawing by reference numerals like characters designating corresponding parts in the several views, our device resembles in general a large T-shaped walking stick of which the horizontal handle is of course the upper end part and the vertical part depending therefrom is integral with the handle.

Said handle or handhold comprises an inverted U-shape member 6 preferably made of light $\frac{3}{4}$ " channel iron, with a rear downwardly directed arm, 6A extending thence forwardly horizontally about 8 inches as 6B thence bent downwardly as at 6C and thence back toward the rear arm about as 6D thence down vertically about 32 or 33 inches as 6E all in a common vertical plane the flanges directed inwardly, or in other words the web part of the channel exposed exteriorly throughout. The lower extremity of the upright part for a distance of about 4 inches is tapered rearwardly or in other words of chisel like shape as at 6F.

7 is another upright member of like channel material in parallelism with and normally spaced from member 6E about $\frac{3}{4}$ " said member also of chisel like terminus at its lower end as at 7F extending upwardly as described, to about the level of shoulder 6D at which height it is bent toward and connected to the upper part of said shoulder as at 7A by welding or riveting (not

shown). See Fig. 1. The two parallel main parts of the device forming a stock thus consist of two spaced apart channel irons with their web parts out or rather their flanged parts extending toward each other.

Just over the lower tapered ends (comprising a pair of jaws) as described, or about 7½-8" from their lower extremities, the two members are pivotally connected on pivots 8 in overlapped parts of two sheet metal U-shaped members 9 10 each secured as at 10 with its face part onto the exterior face of the web of members 6E and 7.

This joint at 8 and the fixed connection of the channels at their upper parts (on under side of 15 the handle) hold the two vertical channel members normally in spaced parallel relation.

Intermediate the ends of the upright, dual stock, (over pivot connection at 8) the bars are further connected by a toggle joint or downwardly directed V-joint, comprising preferably two pairs of links 11R and 11L of which the outer ends of the right hand links 11R are pivoted on a pin 12R in a U-bracket 13R fixed on the inner face of the web of the upright channel 6E, while the corresponding ends of the links 11L are pivoted on a pin 12L in a U-bracket 13L fixed on the inner face of channel 7. The lower and inner ends of all four of the links are pivoted on a pin 14 to which is also pivotally connected the lower end part 15A of a manipulating rod 15 which will presently be described, said rod extending upwardly between the channel members and into the handle portion of the device, as follows:

The upper part of rod 15 extends through the web of the upper extremity of channel 7 and is pivotally secured as at 16 to a finger lever or trigger 17 within the hand hold and which lever is pivotally connected at 18 to a bracket 19 fixed at the inner side of part 6C of the hand hold. The longer part of said finger lever extends rearwardly from pivot 16 toward the rear part of the handle in a downwardly inclined plane.

Obviously when an operator grasps the handle 6 and lever 17 and exerts a squeezing action, lever 17 moves upwardly exerting a powerful pull on rod 15 which in turn opens or straightens the toggles described spreading the parallel bars 6E and 7 intermediate their ends.

Simultaneously the jaw members below pivot 8 are closed with a powerful action to clamp between them, roots 20 of weeds such as dandelions (Fig. 1).

The tapered lower (jaws) ends are normally in spaced parallel relation as long as the main parallel lengths of the bars 6E and 7 are retained parallel to each other.

Now it will be readily understood that the lower pronged ends or jaws are pushed into the ground to straddle the root of a weed, while said prongs are in parallelism. Then the rod 15 is pulled upward to close the jaws on the said root, as above described, and while in root-pinch-
10 ing condition the device is pulled upwardly to extract the weed by its root. After getting the weed out of the ground the operator continues to grip the handle and lever until it is desired
15 to release the weed in a container or on a pile, by simply releasing the squeezing grip when the natural spring action in the bars 6E and 7 tending to go back to normal parallel relation, opens the jaws or prongs below pivot 8 and releases
20 the weed.

For the purpose of forcibly expelling any weeds and roots which may stick between the prongs we provide an expelling device as follows:

21 is a cross head or plunger reciprocally re-
25 tained in and between the flanged parts of the opposite channels 6E and 7 and normally positioned at or just below pivot 8. 22 is a rod fixed in said cross head and extending upwardly between the channels and having its upper end se-
30 cured as at 23 to the lower end part of a sheet metal sleeve 24 inclosing the two channels 6E and 7 just below the hand hold.

Thus when a weed root is stuck between the prongs or jaw members, even after the lever 17 has been released, the operator merely grasps the metal sleeve 24 and pushes downwardly causing the cross-head to move toward the open ends of the prongs and forcibly expel a root or any other obstacle between the prongs.

40 25 is a foot presser member comprising a tri-
angular plate pivotally mounted as at 26 on either of the upright channels and over the pivotal connection 9 of the latter. This plate is provided with integral tongues 25T located to engage the front and rear flanges of the channel simulta-
45 neously, when the upper edge of the member is positioned at right angles to the channels, but permit swinging of the member up to and alongside of the channel in a least obstructive position
50 when not in use.

The operator merely pressed down on the ex-
tended lever, with his foot, to push the prongs into the ground when the latter is hard or dry.

In the broken out portion of the sleeve 24 (in
55 Fig. 1) is shown a tension coil spring 27, one end of which is connected to the upper part of either channel bar 6E or 7 and the other end to the lower end part of the sleeve, preferably on the pin
23. This spring retrieves or draws the expelling device back to its upper normal position after it
60 has been used to expel a root, etc.

It will be noted that in our simple construction the parallel channels are simply sprung apart to forcibly and very effectively close the jaws
65 6F—7F on roots to be extracted, said jaws and channels normally springing back to their original parallel positions when the operator's grip on the handle and lever is eased. In other words the normal tendency of the parallel bars to re-
70 turn to parallel relation is utilized to open the jaws and release roots and other objects grasped by them.

In modified forms of the device it may be used for pulling vegetables, for transplanting small
75 plants, removing obstacles from pipes etc.

In Fig. 2, 28 designates a pair of vertically aligned apertures, preferably oval shaped, in the web of both jaw members near their lower ends. In Fig. 4 the inside surface of both jaw members is shown corrugated or roughened at 29. The 5 said apertures and roughening increase considerably the friction hold on roots. For example when such jaws are clamped on a root, parts of it are squeezed into the apertures and thus afford greater resistance to slippage.

Modifications in structural detail may be embodied without departing from the scope and spirit of our invention. The handle 6 may be a rectangular frame to the under side of which the upper ends of the stock members 6E and 7 are 15 affixed in any suitable manner.

We claim:

1. In an uprooting device of the class described, a horizontally disposed hand hold, a main stock extending downwardly from the under side of 20 said hand hold integrally and comprising a pair of bars normally in parallelism, the lower extremities of said bars tapered and comprising a pair of spaced apart jaws, pivot means above said jaw parts connecting the two bars, a toggle between said pair of bars and also connecting the two bars intermediate the said pivot connection and the handle, trigger means within the handle and an operative connection between said trigger means and the toggle to forcibly spread the 25 bars above the said pivot and simultaneously close the said jaws.

2. The structure specified in claim 1, and a plunger member reciprocally retained between said jaw members, a sleeve member slidably mounted and inclosing the upper part of said stock, a plunger rod connecting said sleeve and the plunger, to manipulate the plunger longitudinally of and between the jaws for the purpose set forth.

3. In an uprooting device of the class described, a horizontally disposed hand hold, a main stock extending downwardly from the under side of 35 said hand hold integrally and comprising a pair of bars normally in parallelism, the lower extremities of said bars tapered and comprising a pair of spaced apart jaws, pivot means above 40 said jaw parts connecting the two bars, a toggle between said pair of bars and also connecting the two bars intermediate the said pivot connection and the handle, trigger means within the handle and an operative connection between said trigger 45 means and the toggle to forcibly spread the bars above the said pivot and simultaneously close the said jaws, said trigger means consisting of a lever within the handle and pivotally connected to the front end part of the handle, and a rod extending downwardly from said trigger lever, between the bars of the stock and connected at its lower end to the toggle, as shown and de- 50 scribed.

4. A weeder implement comprising a horizontally disposed hand hold frame, a pair of bars ex-
tending downwardly in parallelism from the under side of said hand hold frame, the lower 55 extremities of said pair of bars being tapered downwardly and comprising a pair of jaws, pivot means connecting said parallel bars above said jaw parts, toggle means intermediate the upper ends and the said pivot means of the parallel 60 bars and comprising links in V-arrangement and connected at their outer ends to the adjacent inner faces of the parallel bars, a lever within the handle comprising a trigger, a rod connect-
65 ing said trigger lever and the toggle links to 70
75

spread the toggle and correspondingly spreading the bars to simultaneously close the jaw members when the trigger member is grasped with the handle, the bar members subsequently assuming a normal parallel relation and opening the jaws when the trigger is released.

5. The structure specified in claim 4, and a foot pressure bracket pivotally mounted on one of said parallel bars, over the jaws, and comprising a metal plate with stop lug on its edge parts to

retain the bracket with an upwardly exposed edge at right angles to the stock.

6. The structure specified in claim 4, in which said jaw members are provided each with a number of apertures adjacent its lower end, and the 5 inner faces of said jaw members being roughened, to facilitate holding and clamping action of the jaws.
